HARRY ARTHUR FOOTHORAP, OF HARRISBURG, PENNSYLVANIA, ASSIGNOR TO ELLIOTT-FISHER COMPANY, OF HARRISBURG, PENNSYLVANIA, A CORPORATION OF DELAWARE.

PLATEN EQUIPMENT FOR TYPEWRITING-MACHINES.

1,375,749.

Specification of Letters Patent. Patented Apr. 26, 1921.

Original application filed February 6, 1911, Serial No. 606,933. Divided and this application filed June 11, 1918. Serial No. 239,488.

To all whom it may concern:

Be it known that I, HARRY ARTHUR FOOTHORAP, citizen of the United States of America, residing at Harrisburg, in the county of Dauphin and State of Pennsylvania, have invented certain new and useful Improvements in Platen Equipments for Typewriting-Machines, of which the following is a specification.

10 This invention relates to a novel platen equipment for typewriting machines, and more particularly to a novel arrangement of work holding and impression transferring elements designed to facilitate certain 15 classes of work such as condensed statement, toll slip and other forms of billing, as for instance by telephone companies performed by what are known as flat platen typewriting machines.

20 The mechanism shown in the accompanying drawings is also shown and described in applicant's copending application for Letters Patent of the United States, Serial No. 606,933, filed February 6, 1911, and allowed 25 November 16, 1917, of which this is a divisional application. Only so much of the mechanism disclosed in said copending application as is necessary to the understanding 30 of the features of the invention claimed herein is shown and described in the present application. For a complete description of the mechanism herein shown and its associated parts reference may be had to said copending application.

35 One of the objects of the invention is to so combine and arrange a platen and a plurality of transfer mediums or web sections that the same may be brought into intimate relation with each other and with a plurality 40 of work elements or expeditiously separated to facilitate the displacement, replacement or adjustment of the work sheets.

45 Another object is to place under control of the operator's foot the manipulation of parts necessary to the accomplishment of the object first stated, to the end that the operator may be left the greatest possible freedom for the manipulation of the work sheets.

50 To the accomplishment of the above recited objects and others which will more fully hereinafter appear, one embodiment of the invention resides in the construction and

arrangement of parts illustrated in the accompanying drawings, described in the following specification, and succinctly defined in the appended claims.

In said drawings:

Figure 1 is a top plan view of a platen constructed, arranged and equipped in accordance with my invention.

Fig. 2 is a bottom plan view thereof.

Fig. 3 is a longitudinal section showing more particularly the relation of the platen and ribbon in the normal or elevated position of the platen also the means for depressing and raising the platen.

Fig. 4 is a longitudinal section on a larger scale of the platen with the parts in the normal or writing position.

Fig. 5 is a similar view showing the platen dropped to space the transfer sections from each other and from the platen to facilitate replacement of the work sheets.

Fig. 6 is a similar view showing the platen arrested after a limited depression.

Fig. 7 is a transverse section on the line 7—7 of Fig. 1, looking toward the rear.

Fig. 8 is a similar view on the line 8—8 of Fig. 1 looking toward the front.

Fig. 9 is a sectional view of one of the ribbon rolls and its mounting, a portion of the parts being broken away to facilitate illustration.

Fig. 10 is a transverse section designed to show more particularly the arrangement of the work sheets and ribbon.

Fig. 11 is a section through the front of the platen frame designed to show the relation of certain parts.

Fig. 12 is a perspective view of the platen operating treadle.

Fig. 13 is a sectional view of the platen operating treadle with the parts locked in normal position.

Fig. 14 is a similar view of the treadle locked in its depressed position.

The machine here shown for illustrative purposes is what is known to commerce as the Elliott-Fisher flat platen typewriter exemplified in Patent No. 573,868.

In general the Elliott-Fisher machine embraces a flat platen associated with which are tracks or guides upon which travel, longitudinally of the platen, a machine frame upon which in turn is mounted a lat-

erally movable carriage which supports key operated printing mechanism arranged to control the movement of the carriage through the medium of an escapement in a manner well understood in the art. Letter spacing is effected by the movement of the carriage on the machine frame and the lines of writing are spaced by moving the frame step by step over the platen.

10 For the purposes of the present disclosure, the machine proper including keys, printing mechanism, etc., has been entirely omitted, not being claimed in this application.

15 The platen frame, as a whole, is indicated at 1. In the present instance this frame comprises side plates 2 provided at their tops with tracks or guides 3 with which the machine frame of a typewriter is intended 20 to coat for line spacing. The side plates 2 are connected by front and rear transverse plates 4 and 5, considerably narrower than the side plates 2 and having their upper edges in a plane somewhat below that of the tracks. In addition to the side and end plates 2, 4 and 5, the frame also includes in 25 the present instance a pair of inner side plates 6 each located adjacent to but somewhat removed from the plates 2 and secured at their ends to the end plates 4 and 5. The inner side plates 6 are somewhat narrower than the end plates and have their upper edges flush with the upper edges of the latter, the inner side plates and the end plates constituting a rectangular frame located within 30 the confines of the platen frame proper and dropped somewhat below the upper edge thereof.

Upon this inner frame is designed to rest 40 in its depressed position a vertically movable flat platen 7, see Fig. 5, which may and preferably does comprise a metal base 7^a having a hard rubber or other suitable covering 7^b. The platen 7 is of considerably less length than the platen frame and is of sufficient width to extend through the side plates 2 which are cut out to accommodate it, as shown in Figs. 4 to 6, and 10. The right hand margin of the platen terminates 50 practically flush with the outer surface of the platen frame, but the left hand edge of the platen is extended considerably beyond the platen frame, and is equipped with a margin guide or gauge 8 to facilitate the positioning of a work sheet 9, see Fig. 55 10, ordinarily known as the master sheet. The gage 8 is formed of metal and comprises an abutment 10 and a guard flange 11, the latter extending over and guarding the edge of the sheet positioned on the platen by the abutment. While this gage 60 may be permanently secured to the platen, it is preferably detachably retained by set screws 8^a.

35 The platen 7 is designed to have con-

siderable vertical movement while retaining its true horizontal position. The extent of this movement is shown by a comparison of Figs. 4 and 5 wherein it will be seen that the platen when in normal position is elevated to cause a work sheet imposed thereon to be clamped against the under side of the tracks or guides 3 and when lowered the platen rests, as heretofore stated, upon the upper edges of the inner side bars 6 of the 75 frame. The platen is supported by an arrangement of levers similar to those employed in lazy tongs.

Depending from the platen adjacent to its respective corners are bearings 12. Between the two front bearings extends a shaft 13 from which in turn are extended a pair of inclined platen supporting levers 14 having their rear ends carried by a shaft 15 afforded bearings in the rear ends of the 80 inner frame bars 6, see Figs. 2 and 3. To the rear bearings 16 are pivoted, by stud shafts or screws 17 a pair of inclined levers 18 having their front ends carried by a transverse shaft 19 afforded bearings adjacent to the front ends of the bars 6. At the intersection of the oppositely inclined bars 14 and 18, said bars are connected by a transverse shaft 20 from which depend a pair of connecting rods 21 having their 85 lower ends connected, as indicated in Fig. 2, to a treadle 22 mounted to swing from a fixed support, as for instance one of the frame bars 23, of the metal table upon which the platen frame is usually supported. The 90 platen is urged toward its elevated position by springs 24 having their upper ends secured to brackets 25 fixed to the frame bars 6 and having their lower ends attached to brackets 26 secured to the connecting rods 95 21, an additional spring 27 extended from a fixed part 28 being secured, if desired, to a cross bar 29 extended between the connecting rods 21.

The treadle 22 is conveniently located for 100 operation by the foot of the machine operator who, by depressing the treadle 22, will swing the platen supporting levers 14 and 18 through the connecting rods 21 and thus depress the platen from its normal position 105 shown in Fig. 4 to its depressed position shown in Fig. 5. Upon the release of the pressure upon the treadle 22 the springs 24 and 27 will restore the platen to its normal or elevated writing position, incidentally clamping the paper between the platen and the under sides of the rails.

It is desirable to have the locking means under the control of the operator's foot. I therefore equip the treadle 22 with two 115 locking bails 30 and 31, one bail serving to lock the platen in its elevated position and the other serving to lock the platen when depressed. The bails 30 and 31 are mounted to swing from a rod 32 extended across 120 130

the treadle and are yieldingly retained in elevated position by springs 33. Each locking bail is provided with a latch 34 or 35 coacting with a latch bar 36 in the form of a cross piece or head at the end of a bar 37 fixed, as shown in Fig. 3, to the table. By reference to Figs. 12, 13 and 14, it will be seen that when the treadle 22 is in its normal elevated position the latch 34 of the locking bail 30 will extend over the latch bar 36 thus preventing the platen from being accidentally depressed in the event of a weight being imposed thereon. When the operator desires to depress the platen, however, he places his foot on the locking bail 30 and by a continuous movement first operates the bail to withdraw the latch 34 and to then depress the treadle 22 and with it the platen. When the treadle has been thus depressed the latch 35 of the locking bail 31 will engage the under side of the latch bar 36 thus locking the treadle in its depressed position.

The operator may now manipulate the work sheets and when he is ready to restore the parts to normal position, it is simply necessary for him to depress the bail 31 with his foot, thus releasing the treadle and allowing the springs 24 and 27 to restore the platen and treadle to their elevated positions where they are automatically locked by the latch 34 and the bail 30.

Under certain conditions, as for instance in making out toll slips, or where it is not necessary to remove or adjust the master sheet, it is sometimes desirable to limit the depression of the platen and to avoid the automatic locking of the latter in depressed position. To accomplish this result a pair of pivoted platen stops 38 are mounted on the inner sides of the frame plates 2 and are held in either of two positions by springs 39, the movement of the stops on their axes being limited by stop pins 40. By reference to Figs. 4 and 5 it will be seen that the platen stops 38 are normally held in inoperative position, but if desired these stops may be swung to the position shown in Fig. 6 to arrest the downward movement of the platen about midway of its normal movement. When the platen is thus arrested by the stops 38 the treadle 22 will not have dropped sufficiently to allow the catch 35 to engage under the bar 36. Consequently when the platen stops are in use the platen will not be locked down and will immediately rise when the pressure on the treadle is relieved.

For the purpose of transferring the impression made upon the top layer of the folded form to the lower layer of said form and to the base sheet I provide an endless ribbon 42 passed around rollers 43 and 44 located beyond the front and rear edges of the platen 7 and having both its horizontal

sections *a* and *b* constituting transfer elements disposed above the platen, as clearly shown in Figs. 4 to 6. The upper section or element *a* of the ribbon is disposed within the folded form 9^a, that is to say, it extends 70 longitudinally of the platen between the upper and the lower sheets of the form. The lower section or element *b* of the ribbon is similarly disposed between the lower or duplicate sheet of the form and the subjacent or master sheet 9. It will therefore appear that when matter is imprinted upon the bill sheet the record will be transferred through the upper section of the ribbon to the lower sheet of the folded form and 80 through the lower section of the ribbon to the ledger sheet.

It will be noted by reference to Fig. 4 that when the parts are in their normal or writing positions, the platen 7 is sufficiently 85 elevated to clamp the work sheets or elements against the under sides of the rails and that the writing surface of the platen is sufficiently elevated with respect to the rollers 43 and 44 to impart a downward in- 90 clination to those portions of the ribbon which extend to the rolls from the opposite ends of the platen. Furthermore it will be noted that when the platen is dropped, as shown in Fig. 5, it will recede from the ribbon and that the horizontal sections of said ribbon will recede from each other, thus effecting a relative separation of the ribbon sections and platen to facilitate displacement and replacement of the work elements. 100

In order to minimize the depression of the platen necessary to effect this separation of the ribbon sections and the complete recession of the platen therefrom the lower section guide rolls 45 and 46 are located just beyond the opposite ends of the platen and with their upper surfaces somewhat elevated with respect to the lower sides of the rollers 43 and 44. These rollers 45 and 46 constitute supports for the lower 110 section or element *b* when the platen is depressed, as illustrated in Fig. 5. These guide rollers 45 and 46 have their left hand ends journaled in the adjacent side plates of the platen frame and their right hand ends are journaled in bearings 47 supported by the transverse members 4 and 5, see Figs. 1, 7 and 8. Obviously the dropping of the platen will create slack in the ribbon and it is equally obvious that this slack must be 120 taken up and the horizontal sections of the ribbon held taut in order to properly facilitate clean and expeditious handling of the work sheets. For this reason both of the ribbon rollers 43 and 44 are mounted for 125 bodily movement longitudinally of the platen and are placed under tension in opposite directions so that said rollers will recede and thus take up any slack which may be produced in the ribbon from any 130

cause. Each of the rollers 43 and 44 is mounted to rotate freely on a shaft 48 or 49, each shaft having at its opposite ends fixed pinions 50 engaging the under sides 5 of short stationary racks 51, see Figs. 4, 7, 8 and 9, the extremities of said shafts resting in longitudinal slots 52 in the side plates of the platen frame. The shafts 48 and 49 are constantly urged in opposite directions 10 by springs 53 and 54 secured at their outer ends to pins 55 projecting from one of the side plates of the platen frame and having their inner ends coiled about and secured to the shafts 48 and 49, see Figs. 1, 2, 7 15 and 8.

The construction and arrangement of the ribbon and platen as thus far described is original with me, but the drawings disclose, in addition to the recited elements certain 20 others coacting therewith to secure an end-wise feed of the ribbon in a manner not contemplated by my invention.

Briefly, the feed of the ribbon is effected in the following manner: One of the flanges 25 of the ribbon roller 44, to wit the one located at the rear end of the platen, see Figs. 4 to 6, is provided with a knurled periphery designed to be engaged by an eccentric dog 56 which, when in effective engagement with 30 the roller 44, dogs said roller against rotary movement in one direction, to wit the direction of the dotted arrow in Fig. 4. The dog 56 is mounted on a dog carrier 57 mounted to rock on the shaft 49 and having a straight 35 top face 58 which is normally disposed at a slight angle with respect to the under side of the adjacent rail 3 with which said dog carrier is designed to contact when rocked upon the shaft 49. Similarly, the rear 40 guide roll 46 is dogged against rotary movement in the direction of the dotted arrow in Fig. 4 by a spring urged dog 59, said roll being free to rotate in the opposite direction. The inner or front end of the dog 59 45 is extended somewhat to bring it within the path of the downward movement of the platen 7 in order that said dog will be engaged and moved to its releasing position as said platen approaches the downward limit 50 of its movement, see Fig. 5. When the platen moves downward from its normal position, shown in Fig. 4, it will first reach the horizontal plane in which the upper sides of the ribbon rollers are located. Continued 55 movement of the platen will then cause the lower ribbon section *b* to separate from the upper ribbon section *a*, the slack produced being taken up by the recession of the ribbon rollers in accordance with my invention. The upper surface of the platen 60 will then reach the horizontal plane in which the upper sides of the guide rollers 45 and 46 are located and the lower ribbon section will be sustained by said guides while the 65 platen continues its downward movement

to separate it from such lower section, as heretofore described. But for the provision of the dogs 56 and 59 this movement of the parts would not effect a feed of the ribbon, but it will be seen that as the ribbon rolls 70 recede, the rotary movement of the rear roll 44 will by reason of its engagement with the dog 56 rock the dog carrier 57 and as the ribbon rolls reach a given position, the upper surface of the dog carrier will engage 75 the under side of the rail thus arresting further movement of the carrier and rendering effective the action of the dog to prevent rotary movement of the roller 44 in the indicated direction. 80

During the succeeding movement of the platen the lower ribbon section will recede from the upper section and create additional slack which must be taken up. We have seen, however, that the roll 44 has become 85 automatically locked against further rotary movement in the direction of the arrow. Therefore, as the platen continues to recede, the roller 44 becomes, in effect, a direct connection between the rear end of the upper 90 section of the ribbon and the spring 54. Said spring will therefore take up the slack produced in the ribbon, by drawing the roll 44 laterally, thereby taking up the slack occasioned in those portions of the ribbon 95 lying between the opposite ends of the platen and the two rolls 43 and 44, the slack between the platen and the roll 43 being drawn around said roll. The power of the two springs 53 and 54 being equal, the effect 100 of locking the rear roller 44 is that of a direct connection with the rear end of the upper ribbon section which continues around the front roll 43 and is, in effect, anchored to the platen and to the guide roll 46 by 105 the friction between the ribbon and said elements.

Therefore, upon the locking of the roller 44 in the manner described, the spring 54 overbalances the spring 53, in accordance 110 with the well known principle of the movable pulley, and during the rearward movement of the roller 44, subsequent to the locking thereof against rotary movement, the spring 54 takes up the slack in the ribbon 115 as stated. During this action the front roller 43 has no bodily movement, but rotates on a temporarily stationary axis, as the ribbon is drawn around it. As the platen continues to recede there will be no 120 slackening of the ribbon, since the lower section of the latter will rest on the guide rolls and the only effect of the platen movement will be to cause said platen and the sheet imposed thereon to drop away from the ribbon. Finally, the platen will engage and release the dog 59. 125

The rear spring 54 having now lost the advantage which it gained over the spring 53, will now be overbalanced by the spring 130

53 which will cause the further recession of the front ribbon roller 43 from the platen, thus through the medium of the ribbon drawing the rear ribbon roller 44 toward 5 the platen until the two springs 53 and 54 are again in counterbalancing relation with the two rollers equidistant from the position occupied by them at the beginning of 10 the operation. The longitudinal feed of the ribbon will now have been effected and the parts will be in the positions indicated in Fig. 5.

The provision for taking up the slack in 15 the ribbon in a manner to effect an endwise feed thereof is not claimed herein, since the same is the invention of Eugene R. Goll and is described in his Patent No. 1,094,649. The specific construction of the ribbon rollers is not considered material, but by preference they comprise two flanged hubs 60 to 20 which are secured the opposite ends of a surrounded by a rubber or other suitable covering 62, the sleeve, covering and hubs being united by set screws 63. Each roller 25 is confined against endwise movement by a set collar 64.

It is thought that from the foregoing, the 30 construction and operation of the described embodiment of my invention will be clearly understood, but I wish distinctly to reserve the right to effect such changes, modifications or variations of the illustrated structure as may fall fairly within the scope of the protection prayed.

35 What I claim is:

1. The combination with a flat platen 40 adapted to have web sections disposed thereover, of means for effecting movement of the platen, and means for causing a separation 45 of the web sections from each other and from the platen on the movement of said platen.

2. The combination with a platen adapted 45 to have transfer elements disposed thereover, and supports for the transfer elements, said platen, transfer elements and supports being relatively movable to bring the transfer elements and platen into close relation and to effect a separation of the transfer 50 elements from each other and from the platen.

3. The combination with a vertically movable flat platen, with which a plurality of transfer elements are adapted to be associated, 55 separate supports for the transfer elements, the supports for the respective elements being located in different horizontal planes and beyond the confines of the platen, said platen and supports being relatively 60 movable in a vertical direction to bring the transfer elements and platen into intimate relation or to separate the platen from the transfer elements and permit the latter to be sustained in separated relation 65 by the supports.

4. The combination with a vertically movable platen, of two sets of supports located in different horizontal planes, to respectively carry transfer elements that extend between the supports of each set, said platen 70 being movable toward and from a higher plane than the supports for the uppermost transfer element.

5. The combination with a platen for a plurality of transfer elements, of guides, 75 said guides being arranged to dispose the transfer elements over the platen and in separated relation with respect to each other and said platen being movable between the guides to lift one transfer element toward 80 the other.

6. The combination with a flat platen, 85 with which an endless transfer web is adapted to be associated having upper and lower sections disposed over the platen, and guiding means for the transfer web, said guiding means being wholly located beyond opposite edges of the platen and said platen and web sections having relative separative movement.

7. The combination with guiding means 90 for an endless web, of a platen associated with the web, the platen and web guiding means being relatively movable in a vertical direction to separate the web and platen. 95

8. The combination with guiding means 100 for an endless web, of a vertically movable platen associated with the guiding means for the web to effect separative movement of the web and platen.

9. The combination with a pair of web 105 rolls for an endless web; of a vertically movable platen arranged to coact with the web intermediate of the rolls.

10. The combination with a platen, of 110 means for guiding two horizontal web sections over the platen, and tension mechanism for such web.

11. The combination with a platen, of a 115 pair of rollers for carrying an endless transfer web having its upper and lower sections extended between the rollers and over the platen, and reactive means tending to urge the rollers apart.

12. The combination with a vertically 120 movable platen, of rollers mounted independently of the platen for carrying an endless transfer web over the platen, and reactive means tending to impart relative movement to the rollers to keep the transfer web taut.

13. The combination with a vertically 125 movable platen, of a pair of rollers located beyond opposite limits of the platen for carrying an endless transfer web having upper and lower sections disposed above the platen, and guides for the lower section of the transfer web.

14. The combination with a stationary 130 support, of rollers mounted therein for

carrying an endless transfer web extended around the rollers and having horizontal upper and lower web sections, guides for the lower web section, a platen vertically movable and coacting with the web to bring the sections thereof together, said platen being also movable in the opposite direction to permit the separation of the web sections from each other and to remove the platen from the lower web section.

15. The combination with a stationary support, of rollers mounted therein for carrying an endless transfer web extended around the rollers and having horizontal upper and lower web sections, guides for the lower web section, a platen vertically

movable and coacting with the web to bring the sections thereof together, said platen being also movable in the opposite direction to permit the separation of the web sections 20 from each other and to remove the platen from the lower web section, and reactive means tending to effect relative separative movement of the rollers to keep the transfer web taut.

25

In testimony whereof I affix my signature in the presence of two witnesses.

HARRY ARTHUR FOOTHORAP.
